UNITED STATES PATENT OFFICE

2,198,590

ILLUMINATED SIGN

Arthur H. Buckley, Chicago, Ill., assignor of one-half to John F. Keeley, Chicago, Ill.

Application April 24, 1939, Serial No. 269,657

15 Claims. (Cl. 40—77)

The invention relates to illuminated exhibitors or signs.

One object of the invention is to provide an improved illuminated exhibitor or sign for displaying pictorial or advertising matter, which is adapted to intermittently change a picture or other matter and to alternately focus the image on the screen and to bring the image out of focus and produce variations in the image on the screen while the exhibitor remains positioned and is illuminated to retain the image on the screen for attracting and maintaining the attention of observers.

This object is attained primarily by providing mechanism for alternately bringing the sign into and out of focus so that while the sign is in focus, it will be clearly legible and visible and during its movement out of and back into focus it will produce varying color effects.

Another object of the invention is to provide a simple construction for producing this result, by means of a slidable and rotatable drum which carries the exhibitor.

Other objects of the invention will appear from the following detailed description.

The invention consists in the several novel features which are hereinafter set forth and are more particularly defined by claims at the conclusion hereof.

In the drawings: Fig. 1 is a section taken on line 1—1 of Fig. 2, embodying the invention. Fig. 2 is a section taken on line 2—2 of Fig. 1 illustrating the drum in position assumed while the exhibitor thereon is in focus. Fig. 3 is a section taken on line 3—3 of Fig. 1 with the drum in the same position. Fig. 4 is a section similar to Fig. 3, illustrating the cylindrical exhibitor when it has been shifted out of focus for producing an illusion of color effects.

The mechanism embodying the invention is exemplified in a casing or box which is formed of sections to provide convenient access to the exhibitor and its operating mechanism. One section of the casing comprises integral side-walls 10 and a back 11. The other section comprises an integral bottom 14 and a front 12 provided with a window-opening 13 therein. The sections are adapted to be slidably assembled with the bottom 14 fitting on inturned flanges 15 on the side walls 10 and back-wall 11. The top of the casing is formed of a transparent plate 16 supported between angle-strips 17 secured to the side-walls 10 and overlying flanges 18 on the side-walls 10 and backwall 11 and a flange 19 on the front-wall 12. A cylindrically curved trans-

lucent plate 20, for example, of frosted glass, which functions as a screen is mounted in the window-opening 13 and is confined between in-turned flanges 21 and angle-strips 22 which are curved conformably to said plate.

The sign comprises a drum which is rotatable to successively bring sections of approximately 90° at one side thereof into horizontal alignment with the translucent screen 20 and is movable horizontally to and from said screen. The drum comprises an end 24 which has a trunnion 25 fixed to its center and an end 26 which is provided with an out-turned flange 27 which provides a central opening in said end. An electric lamp 28 is stationarily supported on a bracket 29 which is fixed to the bottom 14 of the casing. The supporting nipple 30 for the lamp extends through the opening in end 26 to permit the cylinder to be moved horizontally relatively to the plate 20. The periphery of the drum comprises a cylinder 31 supported on inturned flanges of drum-ends 24, 26 and of translucent material such as ground glass or Celluloid, and an exhibitor sheet 32 wrapped around cylinder 31 on which is printed, painted, or lithographed the picture or matter to be exhibited. This matter is divided into four segments, each with different matter thereon for an equal number of displays. The sectionally cylindrical screen 20 is adapted to expose one segment of the exhibitor so that, upon successive quarter-revolutions of the drum, the sections of the sign will be successively illuminated and projected onto screen 20.

Trunnion 25 on drum-end 24 is slidably supported on a stationary guide-plate 33 which is supported by a bracket 34 which is fixed to the bottom 14 and front 12 of the casing. The flange 27 of drum-end 26 is slidably supported on a bracket 35 which is fixed to the front and bottom of the box. Mechanism is provided for rotating the drum and moving it horizontally to bring the sections of the sign into and out of focus relatively to the translucent screen 20. This mechanism comprises an electric motor 36 and a speed-reducing gearing enclosed with the motor, as well understood in the art, and a shaft 38 driven by the motor through said gearing. A crank-arm 39 is fixed to shaft 38 for continuous rotation by the motor. The drum-shifting mechanism comprises an arm 40 fixed to a shaft 41 which is fulcrumed in lugs secured to the bottom 14 of the casing, and is provided with a forked upper end 42 which straddles the cylindrical outer end of trunnion 25. An arm 43 fixed to shaft 41 is provided with a fork 44 which

straddles the flange 27 on drum-end 26. The oscillation of arms 40, 43 moves the drum bodily to and from the front of the box. A link 45 is connected to the outer end of crank 39 and is provided with a slot 46 for a stud 47 on arm 40. A spring 48 is connected to stud 47 and the casing to press arms 40, 43 forwardly into position to hold the drum in its forward position where its periphery will be substantially concentric with the plate 20. The pressure of spring 48 applied to arm 40 also causes the forked end 42 of said arm to press the trunnion 25 against the guide 33 to limit the forward movement of the drum. During each rotation of crank 39 slot 46 in link 45 results in lost-motion of the link so the drum will remain stationary for a period in its foremost position and, during the remaining portion of each revolution, the outer end of slot 46 will engage trunnion 25 and swing arm 40 rearwardly to move the drum bodily away from plate 20, as illustrated in Fig. 4. Spring 48 will hold trunnion 25 against the outer end of slot 46 during the backward movement of the drum and during its forward movement until the pivotal movement of arm 40 is arrested by stud 25 and guide plate 33. The lost-motion of link 45 occurs after the drum has reached its foremost position so that the drum will remain stationary and the front segment of the exhibitor will remain in focus and exposed for a predetermined period. As the drum is moved rearwardly, it will gradually carry the sign out of focus with respect to screen 20 so that the image of the exhibitor on screen 20 will fade out and variations in color effects will be produced in lieu thereof according to the colors of the picture or descriptive matter on the exhibitor after they pass out of focus.

While the sign on the drum is out of focus a quarter turn will be imparted to the drum on its axis to successively expose the segments of the exhibitor on the drum. This is effected by a tooth 49 on guide 33 and a polygonal portion 25^a of trunnion 25. Toward the end of the backward stroke of link 45 the rear lower corner of polygonal portion 25^a of stud 25 will be engaged by tooth 49 and the arm 40 will continue to move rearwardly so the stud 25 will be rotated a quarter turn as the succeeding flat face of polygonal portion 25^a rides over the top of tooth 49, and onto the rear portion of guide 33. An arm 50 pivoted at 51 to bracket 34 engages the top of polygonal portion 25 of trunnion 25 and is pressed downwardly by a spring 52 so that the drum will be held against rotation by guide 33 and said arm except during the engagements of the stud with tooth 49. This exemplifies simple, power-operated mechanism for intermittently moving the drum and rotating it to bring the sign into and out of focus and to successively bring segments of the exhibitor into position for exposure.

In operation, the motor 36 will continuously rotate shaft 38. Assuming the drum to be in its foremost position, as illustrated in Fig. 3, the lamp 28 will illuminate the segment of the exhibitor adjacent cylindrically curved screen 20. Said segment will be substantially concentric with screen 20 so that an image of the matter on said segment will be projected to and focused on the translucent screen 20 and will be clearly legible to an observer. In the course of each rotation of crank 39, link 45 will intermittently engage and shift arm 40 to move the stud 25 and drum bodily rearward and away from plate 20, as illustrated in Fig. 4. During this movement of the drum, the image of the last exposed segment of the

exhibitor will pass out of focus, fade out, and produce variations of mixed or blended color effects on screen 20 according to the colors used in the exhibitor. As the crank 39 approaches the rear end of its stroke, the rear vertical face of polygonal portion 25^a of trunnion 25 will engage tooth 49 and a quarter of a revolution will be imparted to the drum. Arm 50 engages the top face of polygonal portion 25^a to press its bottom face against the top edge of guide-plate 33 so that the drum will be held against further rotation. During the forward stroke of link 45, spring 48 will hold stud 47 against the front end of slot 46 until the movement of arm 40 is arrested by trunnion 25 and in the position illustrated in Fig. 3, whereupon the drum will remain stationary and the link 45 will move idly until, during the back-stroke of link 45 the front end of slot 46 again engages trunnion 25, whereupon the operation will be repeated. During the idle portion of the stroke of link 45 the drum will remain stationary so that the image of the segment of the exhibitor adjacent screen 20 will be projected onto and focused on screen 20 for a predetermined period before it is moved out of focus. The rotation of the drum for changing the exhibitor segments for exposure occurs while the sign is out of focus so that different color effects will be produced on screen 20 while the sign is out of focus.

A compartment 55 for the display of merchandise is provided in the top of the box or casing. The bottom of the compartment is formed of a translucent plate 56 which is supported by anglestrips 57 secured to the back and sides of the box. The lamp 28 will project light through the exhibitor to the translucent plate 56 forming the bottom of compartment 55 and illuminate the merchandise displayed in said compartment. During the rotation of the drum different color effects will be produced in the compartment for attracting observers to the merchandise.

Having thus described the invention, what I claim as new and desire to secure by Letters Patent is:

1. In an illuminated exhibitor sign, the combination of a casing having a window provided with a curved translucent screen, a conformably curved exhibitor adapted for the passage of light therethrough, illuminating means disposed to project light through the exhibitor onto the screen, and means for moving the exhibitor to and from the screen to alternately focus the image on the screen and to bring the image out of focus and produce variations therein on the screen while the exhibitor remains positioned to retain, and is illuminated to project, the image onto the screen.

2. In an illuminated exhibitor sign, the combination of a casing having a window provided with a curved translucent screen, a conformably curved rotatable exhibitor adapted for the passage of light therethrough, illuminating means disposed to project light through the exhibitor onto the screen, means for moving the exhibitor to and from the screen to alternately focus the image on the screen and to bring the image out of focus and produce variations therein on the screen while the exhibitor remains positioned to retain, and is illuminated to project, the image onto the screen, and means for intermittently rotating the exhibitor to project different arcuate portions thereof onto the screen.

3. In an illuminated exhibitor sign, the combination of a casing having a window provided

with a curved translucent screen, a conformably curved exhibitor adapted for the passage of light therethrough, a rotatable drum on which the exhibitor is mounted, illuminating means disposed 5 to project light through the exhibitor onto the screen, means for moving the exhibitor to and from the screen to alternately focus the image on the screen and to bring the image out of focus and produce variations therein on the screen 10 10 while the exhibitor remains positioned to retain, and is illuminated to project, the image onto the screen, and means for intermittently rotating the drum to bring successive portions of the exhibitor into operative relation with the screen.

15 4. In an illuminated exhibitor sign, the combination of a casing having a window provided with a curved translucent screen, a conformably curved exhibitor adapted for the passage of light therethrough, a rotatable drum on which the exhibitor is mounted, illuminating means disposed 20 to project light through the exhibitor onto the screen, means for moving the exhibitor to and from the screen to alternately focus the image on the screen and to bring the image out of focus 25 and produce variations therein on the screen while the exhibitor remains positioned to retain, and is illuminated to project, the image onto the screen, and means for intermittently rotating the drum while the image from the exhibitor is out 30 of focus.

5. In an illuminated exhibitor sign, the combination of a casing having a window provided with a cylindrically curved translucent screen, a slidably supported exhibitor conformably 35 curved to the screen and adapted for the passage of light therethrough, illuminating means for projecting light through the exhibitor onto the screen, and means for slidably shifting the exhibitor to and from the screen to alternately 40 focus the image on the screen and to bring the image out of focus and produce variations therein on the screen while the exhibitor remains positioned to retain, and is illuminated to project, the image on the screen.

45 6. In an illuminated exhibitor sign, the combination of a casing having a window provided with a cylindrically curved translucent screen, a slidably supported rotatable drum, an exhibitor on the periphery of the drum adapted for the 50 passage of light therethrough, illuminating means for projecting light through the exhibitor onto the screen, means for slidably shifting the drum with the exhibitor thereon to and from the screen to alternately focus the image on the screen 55 and to bring the image out of focus and produce variations therein on the screen while the exhibitor remains positioned to retain, and is illuminated to project, the image on the screen, and means for intermittently rotating the drum 60 while the image from the exhibitor is out of focus.

7. In an illuminated exhibitor-sign, the combination of a casing having a window provided with a cylindrically curved translucent screen, 65 a rotatable drum, an exhibitor on the periphery of the drum adapted for the passage of light therethrough, illuminating means for projecting light through the exhibitor onto the screen, means for intermittently moving the drum relatively to the screen to alternately bring the exhibitor into focus thereon and to cause the exhibitor to fade to produce variations of the image thereof on the screen, and means, operated by the movement of the drum, for intermittently 70 rotating the drum to bring successive portions 75

of the exhibitor into operative relation with the screen.

8. In an illuminated exhibitor sign, the combination of a casing having a window provided with a cylindrically curved translucent screen, 5 an exhibitor curved conformably to the screen and adapted for the passage of light therethrough, a stationary lamp for projecting light through the exhibitor to the screen, the exhibitor being disposed between the lamp and the screen, 10 and means for shifting the exhibitor toward and away from the lamp and screen to alternately focus the image on the screen and to bring the image out of focus and produce variations thereon on the screen while the exhibitor remains positioned to retain, and is illuminated to project, 15 the image on the screen.

9. The combination of a casing having a window provided with a cylindrically curved translucent screen, a drum, an exhibitor around the 20 periphery of the drum adapted for the passage of light therethrough, illuminating means for projecting light through the exhibitor and onto the screen, means for supporting the drum at its ends, comprising a trunnion at one end, a 25 guide on which the trunnion is adapted to slide, means for intermittently shifting the trunnion to move the drum to and from the screen comprising an arm engaging the trunnion, a link and a crank, and an electric motor for driving 30 the crank.

10. The combination of a casing having a window provided with a cylindrically curved translucent screen, a drum, an exhibitor around the 35 periphery of the drum and adapted for the passage of light therethrough, illuminating means for projecting light through the exhibitor and onto the screen, means for supporting the drum at its ends, comprising a trunnion at one end, a 40 guide on which the trunnion is adapted to slide, means for intermittently shifting the trunnion to move the drum to and from the screen comprising a slotted arm engaging the trunnion, a link and a crank, and an electric motor for driving 45 the crank.

11. The combination of a casing having a window provided with a cylindrically curved translucent screen, a drum, an exhibitor around the periphery of the drum adapted for the passage of light to the plate, illuminating means for projecting light through the exhibitor and onto the screen, means for supporting the drum at its ends, comprising a trunnion at one end, a guide on which the trunnion is adapted to slide, spring- 50 means for pressing the trunnion against the 55 guide, means for shifting the trunnion to move the drum to and from the screen comprising a slotted arm engaging the trunnion, a link and a crank, and an electric motor for driving the crank.

12. The combination of a casing having a window provided with a cylindrically curved translucent screen, a drum, an exhibitor around the periphery of the drum, adapted for the passage of light therethrough, illuminating means for 65 projecting light through the exhibitor and onto the screen, means for supporting the drum at its ends, comprising a trunnion at one end, a 70 guide on which the trunnion is adapted to slide, means for shifting the trunnion to move the drum to and from the screen, means operable by the movement of the drum, for intermittently rotating the drum, and an electric motor for operating the shifting means.

13. The combination of a casing having a win- 75

- dow provided with a cylindrically curved translucent screen, a drum, an exhibitor around the periphery of the drum, adapted for the passage of light therethrough, illuminating means for projecting light through the exhibitor and onto the screen, means for supporting the drum at its ends, comprising a trunnion at one end, a guide on which the trunnion is adapted to slide, means for shifting the trunnion to move the drum to and from the screen, the drum and guide being provided with intermittently engaging means for rotating the drum, and a motor for operating the shifting means.

14. In an illuminated exhibitor sign, the combination of a casing having a window provided with a translucent screen, an exhibitor adapted for the passage of light therethrough, illuminating means disposed to project light through the exhibitor onto the screen, and means for moving the exhibitor toward and away from the screen in a plane which will alternately focus the image on the screen and bring the image

out of focus to produce variations therein on the screen while the exhibitor remains positioned to retain, and is illuminated to project, the image onto the screen.

15. In an illuminated exhibitor sign, the combination of a casing having a window provided with a translucent screen, a rotatable exhibitor adapted for the passage of light therethrough, illuminating means disposed to project light through the exhibitor onto the screen, means for moving the exhibitor toward and away from the screen in a plane which will alternately focus the image on the screen and bring the image out of focus to produce variations therein on the screen while the exhibitor remains positioned to retain, and is illuminated to project, the image onto the screen, and means for intermittently rotating the exhibitor to project different arcuate portions thereof onto the screen while the image is out of focus.

ARTHUR H. BUCKLEY.

20
